CLAIM

The ornamental design for packaging, as shown and described.

DESCRIPTION

FIG. 1 is a front perspective view of one side panel portion of a packaging, showing our new design, shown separately to show aspects of the design not visible when combined; FIG. 2 is a rear perspective view of the side panel of FIG. 1;

FIG. 3 is a top plan view of the side panel of FIG. 1; FIG. 4 is a bottom plan view of the side panel of FIG. 1; FIG. 5 is a side elevation view of the side panel of FIG. 1; FIG. 6 is another side elevation view of the side panel of FIG. 1;

FIG. 7 is a front elevation view of the side panel of FIG. 1; FIG. 8 is a rear elevation view of the side panel of FIG. 1; FIG. 9 is a bottom perspective view of a top panel portion of a packaging, showing our new design, shown separately to show aspects of the design not visible when combined; FIG. 10 is a top perspective view of the top panel of FIG. 9; FIG. 11 is a bottom plan view of the top panel of FIG. 9; FIG. 12 is a top plan view of the top panel of FIG. 9; FIG. 13 is a side elevation view of the top panel of FIG. 9; FIG. 14 is another side elevation view of the top panel of FIG. 9;

FIG. 15 is a front elevation view of the top panel of FIG. 9; FIG. 16 is rear elevation view of the top panel of FIG. 9; FIG. 17 is an upper perspective view of the assembled packaging, including two side panels and one top panel; FIG. 18 is a lower perspective view of the packaging of FIG. 17;

FIG. 19 is a top plan view of the packaging of FIG. 17; FIG. 20 is a bottom plan view of the packaging of FIG. 17; FIG. 21 is a side elevation view of the packaging of FIG. 17; FIG. 22 is another side elevation view of the packaging of FIG. 17;

FIG. 23 is a front elevation view of the packaging of FIG. 17;

FIG. 24 is a rear elevation view of the packaging of FIG. 17; FIG. 25 is a front perspective view of one side panel portion of a packaging, showing our new design, shown separately to show aspects of the design not visible when combined; FIG. 26 is a rear perspective view of the side panel of FIG. 25;

FIG. 27 is a top plan view of the side panel of FIG. 25;

(Continued)

FIG. 28 is a bottom plan view of the side panel of FIG. 25; FIG. 29 is a side elevation view of the side panel of FIG. 25; FIG. 30 is another side elevation view of the side panel of FIG. 25; FIG. 31 is a front elevation view of the side panel of FIG. 25; FIG. 32 is a rear elevation view of the side panel of FIG. 25; FIG. 33 is a bottom perspective view of a top panel portion of a packaging, showing our new design, shown separately to show aspects of the design not visible when combined; FIG. 34 is a top perspective view of the top panel of FIG. 33; FIG. 35 is a bottom plan view of the top panel of FIG. 33; FIG. 36 is a top plan view of the top panel of FIG. 33; FIG. 37 is a side elevation view of the top panel of FIG. 33; FIG. 38 is another side elevation view of the top panel of FIG. 33; FIG. 39 is a front elevation view of the top panel of FIG. 33; FIG. 40 is rear elevation view of the top panel of FIG. 33; FIG. 41 is an upper perspective view of the assembled packaging, including two side panels and one top panel; FIG. 42 is a lower perspective view of the packaging of FIG. 41; FIG. 43 is a top plan view of the packaging of FIG. 41; FIG. 44 is a bottom plan view of the packaging of FIG. 41; FIG. 45 is a side elevation view of the packaging of FIG. 41; FIG. 46 is another side elevation view of the packaging of FIG. 41; FIG. 47 is a front elevation view of the packaging of FIG. 41; and, FIG. 48 is a rear elevation view of the packaging of FIG. 41. The broken lines are included for the purpose of illustrating portions of the packaging that form no part of the claimed design. The long-dash short-dash lines show an unclaimed boundary that forms no part of the claimed design.
